UNITED STATES PATENT OFFICE.

CARL M. YODER, OF CLEVELAND, OHIO.

UNIVERSAL WIRING-MACHINE.

1,319,503.

Specification of Letters Patent. Patented Oct. 21, 1919.

Application filed May 24, 1912, Serial No. 699,403. Renewed October 12, 1917. Serial No. 196,349.

To all whom it may concern:

Be it known that I, CARL M. YODER, a citizen of the United States, and resident of Cleveland, in the county of Cuyahoga and State of Ohio, have invented certain new and useful Improvements in Universal Wiring-Machines, of which I hereby declare the following to be a full, clear, and exact description, such as will enable others skilled in the art to which it appertains to make and use the same.

This invention relates to mechanism for bending, beading, or reinforcing the edge or edges of metal strips or sheets and articles made therefrom.

One object of the invention is to provide improved means for bending, beading or reinforcing the edge or edges of metal sheets and articles made therefrom, irrespective of the contour of the sheet metal edge or shape of the article.

Another object of the invention is to provide a plurality of metal bending devices, certain of which are bodily movable relative to each other, whereby the edge or edges of metal strips or sheets and sheet metal articles, irrespective of the contour thereof, may be bent up, beaded or reinforced.

Other objects of the invention will be apparent, to those skilled in the art, from the following description, in which—

Figure 1 is an elevation of a machine for reinforcing metal strips or sheets and articles made therefrom, embodying my invention.

Fig. 1^a is a perspective view of a machine embodying a slightly modified form of the invention.

Fig. 2 is a fragmentary elevation, somewhat enlarged, of the machine shown in Fig. 1.

Fig. 3 is a top plan view of the parts shown in Fig. 2.

Fig. 3^a is a longitudinal sectional view through the bending elements.

Fig. 4 is a view showing the action of the bending devices upon the edge of a metal sheet, the metal sheet, in this instance being flat and its edge straight.

Figs. 5, 6, 7, 8 and 9 are sectional views showing the action of the bending devices.

Figs. 10, 11, 12 and 13 are front, side, rear and top views, respectively, of one of the shaping elements.

55

Fig. 14 is a detail view of the final shaping devices.

Fig. 15 is a detail view of the preliminary bending devices.

60

Fig. 16 is a detail view of the clutch.

65

Reinforcing of the edge of the metal is accomplished by bending over the metal along its edge into a bead or by feeding with the metal a wire and bending or wrapping the metal therearound. In the preferred form of construction, a wire of the desired size is fed with the metal sheet or article to the machine and the metal adjacent the edge thereof is bent around and in snug engagement with the wire.

70

In the drawings, A indicates a suitable standard or support. A' indicates a frame fixed, in any well known manner, to or upon the standard A. The frame A' is preferably provided with two spaced upright members a, a, having suitable bearings C² to receive and support a pair of upper and lower shafts B, B'.

75

The shafts B, B', extend at one side of the frame A' beyond the adjacent upright member a for a purpose to be later set forth. The mechanism for driving one of said shafts, preferably the lower shaft B, may consist of gears B², B³, B⁴ and B⁵ (serving as reduction gearing), a belt pulley B⁶ and a suitable clutch mechanism D. The clutch may comprise pivoted arms D^x and friction band segments D', adapted to be operated by a swinging lever D², link D³, rock arm D⁴, rod D⁶ and foot lever D⁵. D⁷ indicates a spring connected at its opposite ends to the foot lever D⁵ and standard A and tending normally to maintain the lever elevated and the clutch in inoperative position. The foot lever D⁵ is adapted to be moved downwardly; when so operated it throws in the clutch D and connects the pulley B⁶ to the shaft B to drive the latter.

80

D⁸, D⁹, indicate a pair of spur gears fixed to the shafts B', B, respectively, and meshing with each other. The gears D⁸ and D⁹ are preferably of the same size and serve as driving connections to drive the shaft B' from the shaft B at the same rate of speed.

100

C, C' indicates a pair of rolls or bending elements, respectively, fixed to the extended ends of the shafts B, B'. The rolls are shaped for coöperation and service to give the edge of the metal sheet E' a preliminary bend, see Figs. 6 and 15. As shown in this latter figure, the roll C is formed with a groove to provide for the feeding of a wire E² with the sheet metal E'.

10 S' indicates devices for adjusting the shaft B' endwise to provide for varying sizes of wire and thicknesses of metal which may be fed between the rolls C, C'. The adjusting devices S' preferably comprise a rod 1, rotatably mounted in a bearing in one of the uprights *a*. The inner end of the rod 1 is provided with screw threads and fits a screw threaded opening formed in a lug 2 which is fixed to the shaft B. The 15 outer end of the rod 1 is shaped to receive a suitable tool, such as a screw driver, to turn the rod. When the rod 1 is rotated, the screw threaded portion acting on the lug 2, will move the latter in one direction or another, according to the direction that the rod is rotated, to adjust the shaft B.

20 The bearings C² for the shaft B are preferably movable vertically for assembly and disassembly purposes and also to permit adjustment of the bending elements C, C'. As shown, in Fig. 2, the uprights are cut away and open at their upper ends to receive the bearing blocks C². C⁴ indicates a plate mounted upon the top of each upright *a* and formed with a screw threaded opening 3. C³ indicates a rod provided with screw threads and extending through the opening 3. The lower end of the rod C³ bears against the adjacent bearing block C²; and the upper 25 end of the rod C³ is provided with a crank or handle, by means of which the rod can be turned. The bending elements C, C', are spaced from each other a sufficient distance to receive the metal sheet and feed it forwardly while bending its edge laterally. In the event the bending elements C, C' do not engage or bear against the metal sheet with sufficient force, or if they are too close together to receive the sheet, then the rod C³ is rotated in the proper direction to adjust the shaft B upwardly or downwardly.

25 E indicates a platform for supporting the metal sheet E' or work while it is being fed to the bending elements C, C'. By preference, one edge of the platform is bent downwardly, as shown at 4 and secured in any well known manner to the frame A'. F indicates a guide arranged in a position relative to the platform E and bending elements C, C', to guide the work E' to the latter. The 30 guide F is preferably connected to a rod 5 which extends through an opening formed in the adjacent upright *a*. The rod 5 is preferably provided with screw threads to

take nuts 6, which, by engagement with the opposite sides of the upright *a*, secure the rod 5 thereto. By loosening the nuts 6, the rod 5 can be adjusted endwise in the opening to position the guide in proper relationship to the bending elements C, C'.

7, 8, 9, indicate, as entireties, sets of bending devices for progressively bending or forming the upturned metal edge into final shape and around a wire E² when the latter is to be used for reinforcing the metal edge. The bending devices 7, 8, 9, are preferably mounted to bodily move or slide laterally on a base G relatively to each other and the bending elements C, C', about an axis which is preferably arranged slightly in front of but as close to a line cutting the axes of the bending elements C, C', as is possible, and also to rotate on said base, whereby they automatically accommodate themselves to the shape or contour of the sheet metal edge being bent, beaded or reinforced. Of these bending devices, H, I, indicate a pair of supports slidably mounted upon the base G. Each support H, I, preferably comprises upper and lower plates 10, 11, engaging the upper and lower faces of the base G and sets of connectors 11^a which extend through slots *g* in the base G and connect the plates 10, 11, together. Each connector 11^a preferably comprises a screw 11^b and sleeve 11^c therefor, the sleeve serving to maintain the adjacent plates spaced apart and out of binding engagement with the opposite faces of the base G.

35 The guides for each support H, I, preferably comprise a pair of substantially semi-circular ball races 12 formed in the base G and arranged concentric to each other, races 12' formed in the under faces of the plates 10, (one race in each plate), corresponding to the curvature of the races 12, and a series of balls 13 between each pair of races 12, 12'. The balls 13 coöperate with the walls of the races to guide and control the direction of movement of the supports H, I, and at the same time serve as anti-friction bearings to permit easy movement thereof. The slots *g* are elongated and curved concentric to the guides or races 12 to permit unobstructed movement of the connectors 11^a. As shown, the connectors 11^a and plates 11 serve to maintain the plates 10 in operative relationship with the base G.

40 14 indicates a standard having a foot 14^a which is pivotally mounted upon the support H in any well known manner, but preferably by a shaft 8' having a reduced screw threaded end fitting a screw threaded opening in the adjacent plate 10. At its upper end the standard 14 is provided with an arm 14^b from which vertically depend stud shafts 15 carrying bending elements 8^a, 8^b.

45 16 indicates a bracket fixed to and extend-

ing laterally from the standard 14 and arranged to slidably support a bending element H⁴. The bracket 16 is preferably of polygonal shape in cross section and the opening through the bending element H⁴ is shaped to loosely fit the bracket so that it is free to slide thereon endwise but not rotate. The bending element H⁴ preferably comprises a die, the walls H⁵ of which serve to 10 bend the metal edge from the position shown in Fig. 6 to that shown in Fig. 7 and to prevent flexing of the metal and to guide or feed it to the bending elements 8^a, 8^b. From the foregoing description it will be seen that 15 the bending element H⁴ of the bending devices 7 is swingable about the shaft 8^c and also movable or slidable transversely of the direction of movement of the metal E'. The bending devices 7 could be arranged to rotate 20 on an independent pivot, but owing to lack of space between the bending elements C, C' and 8^a, 8^b, I prefer to mount them on the standard 14 of the bending devices 8. Due 25 to the movement of the bending element H⁴ transversely and relative to the elements C, C' and 8^a, 8^b, adequate provision is made for adjustment thereof to insure its coöperation with the latter sets of bending elements.

Of the final bending devices 9, I⁹ indicates a standard having a foot I¹⁰. The foot I¹⁰ is rotatably secured to the support I, preferably in the same manner that the standard 14 is rotatably secured to the support H. I² indicates a pair of stud shafts 30 extending laterally from the standard I⁹ and carrying a pair of bending elements 9^a, 9^b, which serve to bend the metal edge into final form. The bearing for the upper shaft I² is preferably adjustable to permit the 35 bending elements to operate upon different thicknesses of metal and sizes of wires. For this purpose the standard I⁹ is formed with a guideway 17 to receive a vertically movable bearing block. 18 indicates a plate 40 extending across and secured to the upper end of the standard I⁹ by suitable cap screws 18'. The plate 18 is formed with a screw threaded opening through which extends a screw threaded rod 19. At its lower end the 45 rod 19 is adapted to engage the bearing block. By operation of the rod 19, the space between the bending elements 9^a, 9^b may be 50 adjusted as conditions may require.

From the foregoing description it will be 55 seen that the bending devices 7, 8 and 9 are bodily movable or slidable relative to each other and the bending elements C, C', preferably about a common center, and are also rotatable or swingable. In the operation of the machine, the sheet metal E' and wire E² are presented to the bending elements C, C'. As they pass therethrough, the metal edge is bent up to the 60 position shown in Fig. 6. The bent edge

passes into and through the die H⁴, the 65 walls of which bend the metal edge to the position shown in Fig. 7. From the die H⁴ the metal edge passes between the bending elements 8^a, 8^b, by which it is bent to the position shown in Fig. 8, and then between 70 the bending elements 9^a, 9^b, which bend the metal edge into final shape, as shown in Fig. 9. Where the free edge of the metal is 75 curved, as shown in dotted lines in Fig. 3, the bending devices will move or slide laterally and also rotate to accommodate themselves to the exact shape, contour or curvature of the free edge of the metal sheet. As the bending devices both rotate and move laterally they will adjust themselves to an 80 edge which is curved on a relatively large or small radius. As shown in Fig. 3, the bending elements C, C' are disposed in a vertical plane which is substantially midway between the opposite ends of travel or movement of the bending devices 7, 8 and 9. Accordingly, the bending devices will accommodate themselves to metal sheets having edges curved in either direction, also sheets having compound curved edges or both 85 curved and straight edges.

In Fig. 1^a I have shown a modified form of construction in which the bending elements 7, 8 and 9 are slidably and pivotally mounted on a vertically arranged plate or 90 table G', instead of a horizontal base G. In this form of construction I prefer to form the adjacent upright a and plate G' integral as shown in Fig. 1^a. This modified form of construction is particularly adapted for reinforcing the edges or circumferential rims of metal articles, such as funnels, tubular 95 members, cans and receptacles.

To those skilled in the art of making mechanism of the class described, many 100 alterations in construction and widely differing embodiments and applications of my invention will suggest themselves, without departing from the spirit and scope thereof. My disclosures and the description herein 105 are purely illustrative and are not intended to be in any sense limiting.

Having described the invention what I 110 claim as new and desire to secure by Letters Patent is—

1. In combination, a frame, a table thereon, a pair of preliminary shaping rolls, mounted in the frame, a pair of final shaping rolls having sliding and pivotal movement on said table, a bending element 120 mounted on said table intermediate of said pairs of preliminary and final shaping rolls, and having sliding and pivotal movement thereon, and a block having an angular shaping groove cut into its edge and positioned between the preliminary rolls and said bending element.

2. In a beading and wiring machine, in

combination, a frame provided with a table, a pair of rolls mounted on said frame for bending the edge of the sheet metal plate, a horizontal roll and support therefor movable on said table, a device intermediate between said horizontal roll and said pair of rolls, said device being adapted to retain the edge of the metal sheet in its bent over position, and a separate pair of rolls movably supported upon said table for shaping said metal edge about the wire.

3. In a wiring and beading machine, in combination with a standard, a pair of bending rolls, mounted on said standard, means for rotating said rolls, a horizontal roll and a slotted retaining device, supports therefor having sliding and pivotal movements and a last used pair of shaping rolls and supports therefor having sliding and pivotal movements.

4. In a wiring and beading device, a frame, a support for a sheet of metal to be beaded and wired, a pair of preliminary bending rolls mounted in said frame, a slotted device for retaining the bent over edge of the metal and for giving an additional bend thereto, a horizontal roll and a pair of finishing rolls, and supporting means for said finishing rolls, for said horizontal roll, and for said retaining device, said supporting means having sliding and pivotal movements and means for detachably securing said supporting means to said frame.

5. In a beading and wiring machine, a frame, a table thereon, a pair of preliminary bending rolls on said frame, means for rotating said rolls, a horizontal roll, a block slidably mounted on said table, a roll support for said horizontal roll pivoted on said block, an intermediate retaining device having a slot and supported between said first pair of rolls and said horizontal roll, a pair of finishing rolls, a block slideable on said table, and a roll support for said finishing rolls pivoted on said last mentioned block.

6. In a beading and wiring machine, in combination, a frame, a table thereon, guides thereon, a first pair of rolls mounted on said frame, a horizontal roll, an intermediate slotted retaining member, a block slideable on said table in said guides, a roll support for said horizontal roll pivoted on said block, a retaining member having a slot and adjustable on said roll support, a last pair of rolls, a support therefor, a block slideable on said table, and on which said last mentioned support is pivoted.

7. In apparatus of the character described, the combination of a frame, a pair of preliminary bending rolls, a plurality of bending devices, and a support, for each of said devices mounted to freely rotate and move independently of each other bodily laterally on said frame.

65 8. In apparatus of the character described,

the combination of a frame, a pair of preliminary bending rolls, a plurality of sets of bending devices, and a support for each said set of devices mounted to rotate independently of each other and move bodily laterally on said frame relative to said preliminary bending rolls.

9. In apparatus of the character described, the combination of a frame, a pair of bending elements for preliminarily bending a metal sheet, a plurality of sets of bending devices for progressively shaping the bent portion of the metal sheet, and a support for each said set of bending devices, each said support being mounted on said frame and movable laterally thereon independently of and relative to each other and said bending element.

10. In apparatus of the character described, the combination of a frame, a pair of bending elements for preliminarily bending a metal sheet, a plurality of sets of bending devices for progressively shaping the bent portion of the metal sheet, and a support for each said set of bending devices, each said support being mounted on said frame and movable laterally thereon in opposite directions independently of and relative to each other and said bending elements.

11. In apparatus of the character described, the combination of a frame, a pair of elements for preliminarily bending a metal sheet, a plurality of sets of devices for progressively shaping the bent portion of the metal sheet, separate supports for said shaping devices mounted to independently rotate and move laterally on said frame, and a separate shaping device carried by one of said supports.

105 12. In apparatus of the character described, the combination of a frame, a pair of elements for preliminarily bending a metal sheet, a plurality of devices for progressively shaping the bent portion of the metal sheet, separate supports for said shaping devices mounted to independently rotate and move laterally on said frame, and a separate shaping device carried by one of said supports and mounted to move thereon relative to the other shaping device carried by said support.

115 13. In apparatus of the character described, the combination of a frame, a pair of elements for preliminarily bending a metal sheet, a plurality of devices for progressively shaping the bent portion of the metal sheet, supports, one for each of said shaping devices, mounted to move on said frame, on concentric arcs independently of each other in either direction.

14. In apparatus of the character described, the combination of a frame, a pair of elements for preliminarily bending a metal sheet, a plurality of sets of devices for

progressively shaping the bent portion of the metal sheet, supports, one for each set of said shaping devices, mounted to move independently of each other on concentric arcs, 5 the axis of which is arranged substantially in a plane cutting the axes of said preliminary bending elements.

In testimony whereof, I hereunto set my hand this 9th day of May, 1912.

CARL M. YODER.
